REFRIGERATING APPARATUS

Harry B. Hull, Dayton, Ohio, assignor to General
Motors Corporation, Dayton, Ohio, a corpora-
tion of Delaware

Application May 25, 1934, Serial No. 727,542

13 Claims. (Cl. 62—4)

This invention relates to refrigerating apparatus and more particularly to the control of such an apparatus.

Provisions have heretofore been made for automatically and temporarily increasing or permitting the temperature of an evaporator of a refrigerating system to be increased at predetermined timed intervals in order to initiate or effect melting of frost from walls of the evaporator. Such provision has as far as I am aware ordinarily effected periodic defrosting of the evaporator irrespective of the amount of frost accumulated on the walls thereof. It has been found that defrosting of an evaporator of a refrigerating system at predetermined timed intervals is not entirely satisfactory because it quite frequently occurs that the temperature of an evaporator is increased, to effect defrosting thereof, when such defrosting is not necessary. The amount of frost accumulated on the cooling surfaces of an evaporator of a refrigerating system over a predetermined interval of time varies in accordance with certain food products placed in the compartment being cooled by the evaporator. For example, certain food products are of a greater moisture content than other food products and if a large number of food products containing a considerable amount of moisture are placed in a refrigerated compartment in which an evaporator is disposed the cooling surface of the evaporator will be quickly covered or coated with a layer of frost due to the cooling effect produced by the evaporator causing moisture to be withdrawn from the food products and becoming condensed on the cooling surfaces of the evaporator. However, if the number of food products containing a considerable amount of moisture stored in the refrigerated compartment is reduced to a minimum it will require a longer interval of time for the cooling surfaces of the evaporator to become coated or covered with frost. Since it is only after the frost has accumulated on the cooling surfaces of an evaporator to a predetermined thickness that it tends to insulate the evaporator from the air to be cooled thereby and renders the refrigerating system inefficient in operating no advantage is obtained by periodically defrosting the evaporator prior to the time the frost accumulation thereon becomes detrimental.

Periodic defrosting of the evaporator prior to the time the frost thereon becomes detrimental to the operation of the refrigerating system causes temporary non-freezing actions of the evaporator thus retarding fast freezing of substances, contained in trays and placed in thermal contact with the evaporator, to be frozen. In addition, defrosting of an evaporator when not essentially required causes undue strain, and wear on operating parts of the refrigerating system. My invention is therefore directed to overcoming the difficulties and disadvantages of the conventional refrigerating system in which defrosting of the evaporator occurs periodically irrespective of the amount of frost accumulated on the evaporator and has to do with the provision of an improved system in which the evaporator will be defrosted only when defrosting thereof is necessary as determined by the frost formation thereon.

One of the objects of the present invention is to provide an improved refrigerating system including means for automatically and periodically defrosting the evaporator of the system irrespective of the temperature thereof.

Another object of the invention is to provide a refrigerating system with a means for automatically and periodically defrosting the evaporator of the system only when defrosting thereof is necessary.

A further object of the invention is to provide a refrigerating system with means for automatically defrosting the evaporator of the system which means is normally ineffective and rendered effective solely by a predetermined thickness of frost accumulated on the evaporator.

A still further object of the invention is to provide a refrigerating system with a chronometrically operated device, adapted to initiate defrosting of the evaporator of the system at predetermined time intervals, and to construct and associate the device with the system so that it is normally ineffective, thereby permitting the evaporator to produce a refrigerating effect until frost accumulated on walls of the evaporator attains a thickness sufficient to cause inefficient operation of the refrigerating system and so that the device will thereupon become effective to defrost the evaporator.

Further objects and advantages of the present

invention will be apparent from the following description, reference being had to the accompanying drawings, wherein a preferred form of the present invention is clearly shown.

5 In the drawings:

Fig. 1 discloses a refrigerator cabinet having my invention embodied therein and diagrammatically showing certain elements of a refrigerating system associated with the cabinet;

10 Fig. 2 is a front view of a chronometric device associated with the refrigerating system disclosed in Fig. 1 and showing the device in normal position relative to the cooling unit or evaporator of the refrigerating system.

15 Fig. 3 is a view of the chronometric device similar to Fig. 2 but shows the device in a position after having moved a feeler arm associated therewith toward the evaporator of the refrigerating system;

20 Fig. 4 is a view of the chronometric device showing the feeler arm associated therewith moved into engagement with a layer of frost accumulated on a wall of the evaporator and showing an electric switch associated with the device moved into open position;

25 Fig. 5 is an enlarged view taken on the lines 5-5 of Fig. 2 showing certain of the parts associated with the chronometric device in section;

30 Fig. 6 is an enlarged view taken on the lines 6-6 of Fig. 2 showing certain of the parts associated with the chronometric device in section; and

35 Fig. 7 is an enlarged cross sectional view taken on the lines 7-7 of Fig. 2 showing the mounting of certain parts operated by the chronometric device.

Referring to the drawings, for the purpose of illustrating my invention, I have shown in Fig. 1, thereof a refrigerating system comprising a 40 compressor 20 adapted to compress a refrigerant, such as sulphur dioxide, and to forward the refrigerant under pressure through a pipe 21 to a condenser 22 where the compressed refrigerant is liquefied and collected in a receiver 23. From the receiver 23 the liquid refrigerant is forwarded 45 through the supply conduit 24 to an evaporator 25 mounted in the upper portion of a refrigerator cabinet 26. The evaporator may be of any conventional type and is preferably of the sheet metal variety and providing a sharp freezing 50 chamber within the food storage compartment 27 of cabinet 26 for the reception of ice making receptacles or trays 28. Any of the conventional and well-known float, expansion or 55 restriction devices (not shown) may be employed for admitting liquid refrigerant to the evaporator 25 from the conduit 24 or for maintaining a substantially constant level of liquid refrigerant in the evaporator. Liquid refrigerant within the 60 evaporator 25 absorbs heat and vaporizes, this vapor being returned to the compressor 20 through the gaseous refrigerant return conduit or pipe 29. The compressor 20 is driven by an electric motor 31 through suitable belt and pulley connections 32. The motor 31 is supplied 65 with electric energy through an electrical circuit which will be hereinafter more fully described.

A control switch 33, such as the control mechanism disclosed in the patent to Otto M. Summers, No. 1,802,486, issued April 28, 1931, is connected by the pipe or conduit 34 with the low pressure or gaseous refrigerant conduit 29. As the pressure of refrigerant in conduit 29 increases or decreases uniformly in accordance

with the temperature of the refrigerant in evaporator 25 the control switch is actuated by an expansible bellows 36, connected with conduit 34, to normally maintain the evaporator 25 and consequently compartment 27 between predetermined temperature limits by opening and closing an electric circuit leading to motor 31. The switch 33 thus provides alternate operating and idle periods of the motor 31 and compressor 20 in accordance with the temperature of evaporator 25 to cyclically circulate refrigerant through the evaporator. The foregoing description and disclosure of a refrigerating system or apparatus is conventional and well known to those skilled in the art of refrigeration. For this reason the 15 description of the refrigerating system is made brief and the system is only diagrammatically disclosed.

Evaporators employed in refrigerating systems of the type disclosed ordinarily have cooling 20 surfaces exposed to the air within the food storage compartment of a refrigerator cabinet and these cooling surfaces are usually maintained at such low temperatures that moisture condenses and accumulates thereon in the form of a layer 25 of frost. It has been found that frost after accumulating on an evaporator beyond a certain thickness forms a substantially insulating coating thereon and greatly retards transference of heat from the food storage compartment to refrigerant in the evaporator. To retard the transference of heat from the food storage compartment to the evaporator results in prolonged operations of the refrigerant liquefying and circulating unit and causes undue wear and strain on 30 operating parts thereof as previously described. Provisions have heretofore been made to periodically and temporarily render the refrigerant liquefying and circulating unit inoperative automatically at predetermined timed intervals to 40 permit the temperature of the evaporator to increase above its normal high temperature limit in order to melt or cause frost to be removed from the cooling surfaces of the evaporator. As previously explained this automatic and periodic defrosting of evaporators in prior apparatuses has occurred irrespective of the amount or thickness of frost on the evaporator. Consequently evaporators or prior refrigerating apparatuses were defrosted at predetermined timed 50 intervals regardless of whether they needed to be defrosted or not. Thus if a defrosting period of prior apparatuses occurred at the same time that fast freezing of a substance contained in a tray and located in the freezing compartment of 55 the evaporator was desired, the freezing operation of this substance was delayed even though the evaporator did not need to be defrosted. My invention has to do with providing means for periodically defrosting an evaporator of a refrigerating system at predetermined timed intervals and to cause such defrosting at such intervals only after the frost accumulation has attained a thickness on the evaporator sufficient to impede transfer of heat from food products 60 of air in the storage compartment of the refrigerator or to cause prolonged and abnormal operating periods of the refrigerant liquefying and circulating unit.

An electrically operated clock or chronometric 70 device generally designated by the numeral 40 is installed in any suitable location adjacent the evaporator 25 in the refrigerator cabinet 26 (see Fig. 1). This clock or chronometric device may be stationarily mounted in compartment 27 in a 75

predetermined spaced relationship to the side wall of the evaporator 25. The clock or chronometric device includes a conventional synchronous electric motor (not shown) which is continuously operated by its being connected at all times with a source of electric energy. A switch is also associated with the clock or chronometric device and is normally maintained in closed position and is connected in series relation in the electric circuit leading to the control switch 33 and motor 31. The electric circuit which is opened and closed by the control switch 33 for controlling operations of the motor 31 and consequently compressor 20 includes wire 41, wire 42, the switch in the chronometric device 40, wire 43 contacts 44 and 45 of the control switch 33, wire 46 and 47 (see Fig. 1). The electric circuit leading to the synchronous motor in the chronometric device 40 includes wire 48, and wire 49 connected with wire 41. The switch contained in the chronometric device 40 is normally closed and opening and closing of the contacts 44 and 45 of control switch 33 obviously makes or breaks the electric circuit to motor 31. Thus changes in pressure in the gaseous refrigerant lines 29 and 34, corresponding to changes in temperature of the evaporator of refrigerating system, causes the bellows 36 to actuate the movable contact 45 of switch 33 into and out of engagement with stationary contact 44 to cause cyclical operations of the motor 31 in response to demands placed on the refrigerating system.

Referring now to Figs. 2 to 7 inclusive it will be noted that the chronometrically operated timing device comprises a housing 55 located within the cover or enclosure of the device 40. Any suitable or well-known type of clock or timing device including a synchronous motor (not shown) may be located within the housing 55 and may comprise a plurality of gears or the like for causing rotation of a shaft 56 which extends outwardly of the housing 55 (see Figs. 6 and 7) at any desired or predetermined speed. Shaft 56 has a shoulder 57 formed thereon to provide a shank portion 58 which serves as a pivot point for an arm 59. The function and operation of arm 59 will be more fully described hereinafter. A second shoulder 61 formed on shank portion 58 of the shaft 56 provides a second shank portion 62. A shoulder 63 formed on shank portion 62 provides another shank portion 64 on shaft 56 which is squared in cross section for a purpose to be presently described. The remainder of shaft 56 extending outwardly from the shoulder and shank portions just described is reduced in diameter and is threaded as at 66. After the arm 59 has been placed over the shank portion 58 of shaft 56 a member 67, having a cam portion 68 provided thereon, (see Figs. 2, 3, 4, and 6) is then positioned on the shank portion 62 of shaft 56. A disc 70 having a squared opening therein is then positioned upon the squared shank portion 64 of shaft 56. Another disc 71 is placed over disc 70 and the member 67, disc 70 and the disc 71 are then held in position upon shaft 56 by a nut 72 threaded upon the threads 66. Member 67 and disc 71 are prevented from being rotated relative to shaft 56 and relative to one another by the squared opening in disc 70 receiving the squared portion 64 of the shaft 56 and by virtue of the provision of a finger 74, formed on disc 71, which passes through an elongated slot 75, provided in disc 70, and through an opening 76 formed in member 67 (see Fig. 7). Thus it is apparent that as

shaft 56 is rotated by the motor of the time or chronometric device, disposed within the housing 55, the parts just described will also be rotated. The chronometric device may be of a design to cause the shaft 56 to be rotated a complete revolution in any predetermined number of hours or days according to the interval of the time desired between defrosting periods. The arrangement and association of the parts designated by the numerals 67, 70, 71 and 72 with 10 the chronometric device 40 are such that they permit adjustment thereof relative to the device 40 to cause defrosting periods to be initiated at certain desired times. For example, these parts may be moved or adjusted relative to the shaft 15 56 of device 40 to cause a defrosting period to be initiated at twelve o'clock midnight instead of during the day when refrigeration is not desired to be interrupted.

Since my invention relates to a refrigerating 20 system in which a chronometrically operated device is adapted to render the refrigerant liquefying and circulating unit of the system inoperative periodically but only when a predetermined amount or thickness of a layer of frost has accumulated on the evaporator some provision must be made to render the electric switch, associated with and adapted to be actuated by the chronometrically operated device, ineffective at a time when a defrosting period arrives unless 25 the evaporator is coated with a certain predetermined layer of frost. Therefore, I associate a mechanism with the timing or chronometric device for operating a feeler which controls or governs operation of an electrical switch adapted 30 to be actuated by the device. The electric switch associated and adapted to be actuated by the chronometric device to break the electric circuit leading to control switch 33 of the refrigerating system includes a small glass tube 79 having a 35 quantity of mercury 80 sealed therein (see Figs. 3 and 4). The mercury 80 is adapted to bridge a pair of contacts 81 extending into the tube 79 and connected with the wires 42 and 43. The mercury tube 79 is mounted within a plurality 40 of arms 82 secured to or formed on a bracket 83. Bracket 83 includes a pair of legs 84. A shaft or stud 85 passes through the legs 84 and through a support 86, secured to the top wall of housing 55 (see Fig. 6), to pivotally mount the bracket 83 50 thereon. One of the legs 84 provided on bracket 83 extends downwardly a greater distance than the other leg and has a slot 87 (see Figs. 3 and 4) formed therein. The slot 87 receives a pin 88 secured to the upper end of arm 59 to cause 55 movement of bracket 83 to actuate the mercury switch about its pivot point 85 upon movement of arm 59. A link 91 is connected with arm 59 by a loose connection 92 and link 91 is connected with another arm 93 by a loose connection 94. 60 The arm 93 extends upwardly and includes a hook portion 96 which carries a feeler 97. The feeler 97 is loosely or pivotally mounted on hook portion 96 by screw 98 so as to permit the flat outer surface thereof to engage frost accumulated on the wall of the evaporator 25 which wall is fragmentarily represented in Figs. 2, 3, 4 and 5 of the drawings. It will be noted that feeler 97 and end or hook portion 96 of arm 93 may extend or may be moved outwardly of the 70 casing or housing of the device 40 through an opening 99 provided therein (see Figs. 1 and 2). An arm 101 is pivotally mounted as at 102 upon a wall of the housing or box 55, which contains the chronometric device or mechanism, and this 75

arm 101 has a pin or shaft 103 extending therethrough and through the arm 93 to lock arm 101 and arm 93 together (see Fig. 5). The pin or shaft 103 also carries a roller 104 in alignment with the edges of the member 67 so as to be engaged by the cam 68. The pin or shaft 103 further serves as a fulcrum point for movement of the arm 93 relative to arm 101 as will be more fully described hereinafter. An indicator finger 105 is secured in any suitable manner to housing 55 and has a pointer registering with numerals or the like provided on disc 70. A spring 107 has its one end secured to the movable pin 88, carried by the arm 59, and has its opposite end secured to a peg or pin 108 stationarily mounted on and extending from a wall of the housing 55. The screw or stud 94 which connects link 91 with arm 93 serves as a stop for arm 93, link 91 and arm 59 since the spring is under tension at all times thereby tending to maintain the link, arms, etc., of the mechanism described in a neutral position as shown in Fig. 2 so that roller 104 always engages the edge surface of member 67 which has the cam 68 formed thereon. It is apparent, that since roller 104 is always held in engagement with member 67, the cam 68 when rotated by the chronometric device, moves into engagement with roller 104 and arms 93 and 101 will be moved to the left as viewed in Fig. 3. This movement causes link 91 to move arm 59 in a clockwise direction about its pivot point, shaft 56, a short distance which is insufficient to trip the mercury switch. The movement just described occurs only when there is no or a very thin layer of frost on the walls of the evaporator 25, and is illustrated in Fig. 3 of the drawings to show that the chronometrically operated device is normally ineffective for rendering the refrigerant liquefying and circulating unit inoperative to cause defrosting of the evaporator. However, should the outward movement of arm 93 to the left as viewed in the drawings, be resisted or prevented, such for example, as by a layer of frost 111 as shown in Fig. 4, the portion 45 of arm 93 located below the pin 103 and roller 104 will be caused to move in a clockwise direction about the fulcrum pin 103 when the cam 68 engages or moves the roller 104. As shown in Fig. 4 the feeler 97, attached to the upper 50 end 96 of arm 93, has engaged the abnormal layer of frost 111 on the wall of the evaporator 25 and has caused movement of arm 93 relative to arm 101 and has caused link 91 and arm 59 to be moved a greater distance to the left than 55 normally occurs. This abnormal movement of these arms etc., is sufficient to tilt bracket 83 beyond the dead center of its pivot point 85 relative to the pin 88 to render the mercury switch and consequently the chronometric device 40 effective for initiating a defrosting period. Tilt- 60 ing of the mercury switch, associated with bracket 83, as described causes the mercury 80 to flow to the end of the tube 79, opposite the end thereof in which the contacts 81 are disposed, and thus breaks the electric circuit through wires 42 and 43. Wires 42 and 43 being connected in series with the source of electric current leading to the control switch 33 obviously render the refrigerant liquefying and 65 circulating unit inoperative. The duration of the defrosting or inoperative period of the refrigerant liquefying and circulating unit may be determined by the size of the cam 68 in accordance with the time required to cause a complete

revolution of the member 67. The feeler member 97 is preferably constructed of a poor heat conducting material such for example as bakelite or hard rubber so as to prevent its rapid entrance into the layer of frost or ice 111 on the evaporator 25 as the case would be if the feeler 97 was of a good heat conducting material. Therefore the feeler member 97 does not melt the frost or ice 111 on evaporator 25 with which it contacts any faster than melting of the frost 10 occurs over other portions of the evaporator. In fact, it has been found that the feeler 97 blocks off or isolates that portion of the layer of frost or ice with which it contacts from the relatively warm air circulating within the food 15 storage compartment 27 of the cabinet 26. This, therefore, insures that all portions of the evaporator will be defrosted prior to the time the frost or ice under the feeler 97 melts and prior to the time when the cam 68 moves away from 20 the roller 104 to cause the refrigerating system to again become operative. After the desired length of time allotted for causing defrosting of ice 111 from walls of evaporator 25 has elapsed, the continuous operation of the chronometric device moves cam 68 away from and out of engagement with the roller 104. Spring 107 then moves arm 59 in a counter-clockwise direction about its pivot thus moving link 91, arm 93, and arm 101 to the right or into a position as shown 30 in Fig. 2. This movement causes the head of the pivot pin 94 to engage the edge of arm 101 to prevent further movement of arm 93 to the right and to cause roller 104 to engage the cylindrical edge surface of member 67. This latter 35 movement, created by the spring 107, also causes the mercury switch to be tilted off center or to the right as shown in Fig. 2, relative to its position shown in Fig. 4, to cause the mercury 80 to again bridge the contacts 81 for completing the 40 electric circuit to the control switch 33. After the chronometric device 40 has caused elements associated therewith to move in the position above described and shown in Fig. 2, the refrigerant liquefying and circulating unit 45 continues in its cycles of operation under the control of switch 33. The cam 68 associated with and rotated by the chronometric device may make one or more complete revolutions, in an endeavor to initiate defrosting periods, before a 50 layer of frost or ice of sufficient thickness has accumulated on the walls of the evaporator 25 to render the device operative to cause defrosting of the evaporator. When the cam 68 has made a complete revolution to actuate roller 55 104, arm 93, arm 101 and feeler 97 from the positions shown in Fig. 2 of drawings into the position shown in Fig. 3 and when there is a very thin layer of frost only present on the walls of the evaporator 25 the feeler 97 is permitted to be moved to the left or toward the evaporator 25 without being stopped by the ice formation. This movement does not cause link 60 91 and arm 59 to move a sufficient distance to actuate the mercury switch of the device and therefore the chronometric device 40 is maintained ineffective for causing defrosting of the evaporator until a predetermined thickness of frost or ice has formed on walls of the evaporator. When movement of the feeler 97 of the 65 mechanism toward a wall of the evaporator 25 is blocked or prevented by a layer of frost or ice on a wall of the evaporator as shown in Fig. 70 4, and as previously described, the mechanism functions to tilt the mercury switch and cause 75

the electric circuit leading to the control switch 33 to be opened.

It will be apparent from the foregoing that I have provided an improved refrigerating system 5 of the type in which a chronometrically operated means is employed to cause the evaporator of the system to be periodically defrosted at predetermined intervals of time but which is normally maintained ineffective and rendered effective 10 only after a predetermined amount or thickness of frost has accumulated on walls of the evaporator. My improved system thereby eliminates the occurrence of defrosting periods, that are automatically initiated at predetermined intervals of time, unless a certain amount or thickness 15 of frost has accumulated on the walls of the evaporator thus insuring defrosting of the evaporator only when necessary. This feature renders my refrigerating apparatus more efficient and 20 more desirable than a system in which there is a means which causes periodical defrosting of the evaporator at timed intervals irrespective of the condition of the evaporator.

While the form of embodiment of the invention 25 as herein disclosed, constitutes a preferred form, it is to be understood that other forms might be adopted, all coming within the scope of the claims which follow.

What is claimed is as follows:

causing the temperature of said cooling element to increase temporarily above the normal predetermined high temperature limit thereof, said chronometrically operated means being normally ineffective, a member actuated by operation of 5 said chronometrically operated means into close proximity to said cooling element, and said member being adapted after a predetermined thickness of frost has accumulated on the cooling element to engage the frost and cause said chronometrically operated means to be rendered effective. 10

4. Refrigerating apparatus including a cooling element disposed in a compartment to be refrigerated and having cooling surfaces upon which 15 frost accumulates, means connected with said cooling element and adapted to circulate a refrigerant medium therethrough, means for controlling the operation of said refrigerant circulating means to normally maintain said cooling 20 element between predetermined temperature limits, chronometrically operated means for causing the temperature of said cooling element to increase temporarily above the normal predetermined high temperature limit thereof, said 25 chronometrically operated means being normally ineffective, a cam actuated by operation of said chronometrically operated means, and an arm associated with said cam and movable thereby into close proximity to said cooling element, said 30 arm being adapted after a predetermined thickness of frost has accumulated on the cooling element to engage the frost and cause said chronometrically operated means to be rendered effective. 35

5. Refrigerating apparatus including an evaporator disposed in a compartment to be refrigerated and having cooling surfaces upon which frost accumulates, a refrigerant liquefying and circulating unit operatively connected with said evaporator, means for controlling the operation of said unit to cyclically circulate a refrigerant medium through said evaporator to normally maintain the temperature thereof between predetermined limits, chronometrically operated 40 means for causing the temperature of said evaporator to increase temporarily above the normal predetermined high temperature limit thereof, said chronometrically operated means being normally ineffective, a member actuated by operation of 45 said chronometrically operated means into close proximity to said evaporator, and said member being adapted after a predetermined thickness of frost has accumulated on the evaporator to engage the frost and cause said chronometrically operated means to be rendered effective. 50

6. Refrigerating apparatus including an evaporator disposed in a compartment to be refrigerated and having cooling surfaces upon which frost accumulates, a refrigerant liquefying and circulating unit operatively connected with said evaporator, means for controlling the operation of said unit to cyclically circulate a refrigerant medium through said evaporator to normally 60 maintain the temperature thereof between predetermined limits, chronometrically operated means for causing the temperature of said evaporator to increase temporarily above the normal predetermined high temperature limit thereof, said chronometrically operated means being normally ineffective, a cam actuated by operation of 65 said chronometrically operated means, and an arm associated with said cam and movable thereby into close proximity to said evaporator, 70

30 1. Refrigerating apparatus including a cooling element disposed in a compartment to be refrigerated and having cooling surfaces upon which frost accumulates, means connected with said cooling element and adapted to circulate a refrigerant medium therethrough, means for controlling the operation of said refrigerant circulating means to normally maintain said cooling element between predetermined temperature limits, chronometrically operated means for causing the temperature of said cooling element to increase temporarily above the normal predetermined high temperature limit thereof, said chronometrically operated means being normally ineffective, and means for rendering said chronometrically operated means effective after a predetermined amount of frost has accumulated on the cooling surfaces of said cooling element.

2. Refrigerating apparatus including an evaporator disposed in a compartment to be refrigerated and having cooling surfaces upon which frost accumulates, a refrigerant liquefying and circulating unit operatively connected with said evaporator, means for controlling the operation of said unit to cyclically circulate a refrigerant medium through said evaporator to normally maintain the temperature thereof between predetermined limits, chronometrically operated means for causing the temperature of said evaporator to increase temporarily above the normal predetermined high temperature limit thereof, said chronometrically operated means being normally ineffective, and means for rendering said chronometrically operated means effective after a predetermined amount of frost has accumulated on the cooling surfaces of said evaporator.

3. Refrigerating apparatus including a cooling element disposed in a compartment to be refrigerated and having cooling surfaces upon which frost accumulates, means connected with said cooling element and adapted to circulate a refrigerant medium therethrough, means for controlling the operation of said refrigerant circulating means to normally maintain said cooling element between predetermined temperature limits, chronometrically operated means for

said arm being adapted after a predetermined thicknesses of frost has accumulated on the evaporator to engage the frost and cause said chronometrically operated means to be rendered effective.

- 5 7. Refrigerating apparatus including an evaporator disposed in a compartment to be refrigerated and having cooling surfaces upon which frost accumulates, a refrigerant liquefying and 10 circulating unit operatively connected with said evaporator, means normally effective for controlling the operation of said unit to cyclically circulate a refrigerant medium through said evaporator to maintain the temperature thereof 15 between predetermined limits, a switch for rendering said normally effective control means ineffective to cause the temperature of said evaporator to increase temporarily above the normal predetermined high temperature limit thereof, 20 chronometrically operated means for actuating said switch, said chronometrically operated means being normally ineffective, and means for rendering said chronometrically operated means effective after a predetermined amount of frost 25 has accumulated on the cooling surfaces of said evaporator.

8. Refrigerating apparatus including an evaporator disposed in a compartment to be refrigerated and having cooling surfaces upon which frost accumulates, a refrigerant liquefying and 30 circulating unit operatively connected with said evaporator, an electrical circuit and a normally effective switch interposed therein for controlling the operation of said unit to cyclically circulate 35 a refrigerant medium through said evaporator to maintain the temperature thereof between predetermined limits, a second switch interposed in series relation with said normally effective control switch in said electrical circuit 40 for rendering said control switch ineffective to cause the temperature of said evaporator to increase temporarily above the normal predetermined high temperature limit thereof, chronometrically operated means for actuating said second 45 named switch, said chronometrically operated means being normally ineffective, and means for rendering said chronometrically operated means effective after a predetermined amount of frost 50 has accumulated on the cooling surfaces of said evaporator.

9. Refrigerating apparatus including a cooling element disposed in a compartment to be refrigerated and having cooling surfaces upon which frost accumulates, means connected with 55 said cooling element and adapted to circulate a refrigerant medium therethrough, means for controlling the operation of said refrigerant circulating means to normally maintain said cooling element between predetermined temperature 60 limits, chronometrically operated means for causing the temperature of said cooling element to increase temporarily above the normal predetermined high temperature limit thereof, said chronometrically operated means being normally 65 ineffective, a member actuated by operation of said chronometrically operated means into close proximity to said cooling element, and said member being adapted, after a predetermined thickness of frost has accumulated on the cooling 70 element, to move in a plane substantially at right angles to the exterior of the layer of frost into engagement with the frost to cause said chronometrically operated means to be rendered effective.

- 75 10. Refrigerating apparatus including a cool-

ing element disposed in a compartment to be refrigerated and having cooling surfaces upon which frost accumulates, means connected with said cooling element and adapted to circulate a refrigerant medium therethrough, means for controlling the operation of said refrigerant circulating means to normally maintain said cooling element between predetermined temperature limits, chronometrically operated means for causing the temperature of said cooling element 10 to increase temporarily above the normal predetermined high temperature limit thereof, said chronometrically operated means being normally ineffective, a cam actuated by operation of said chronometrically operated means, and an arm 15 associated with said cam and movable thereby into close proximity to said cooling element, said arm being adapted, after a predetermined thickness of frost has accumulated on the cooling element, to move in a plane substantially at 20 right angles to the extension of the layer of frost into engagement with the frost to cause said chronometrically operated means to be rendered effective.

11. Refrigerating apparatus including an evaporator disposed in a compartment to be refrigerated and having cooling surfaces upon which frost accumulates, a refrigerant liquefying and circulating unit operatively connected with said evaporator, means for controlling the operation 30 of said unit to cyclically circulate a refrigerant medium through said evaporator to normally maintain the temperature thereof between predetermined limits, chronometrically operated means for causing the temperature of said evaporator to increase temporarily above the normal predetermined high temperature limit thereof, said chronometrically operated means being normally ineffective, a member actuated by operation of said chronometrically operated means 35 into close proximity to said evaporator, and said member being adapted, after a predetermined thickness of frost has accumulated on the evaporator, to move in a plane substantially at right angles to the extension of the layer of frost into 40 engagement with the frost to cause said chronometrically operated means to be rendered effective.

12. Refrigerating apparatus including an evaporator disposed in a compartment to be refrigerated and having cooling surfaces upon which frost accumulates, a refrigerant liquefying and circulating unit operatively connected with said evaporator, means for controlling the operation of said unit to cyclically circulate a 55 refrigerant medium through said evaporator to normally maintain the temperature thereof between predetermined limits, chronometrically operated means for causing the temperature of said evaporator to increase temporarily above the normal predetermined high temperature limit thereof, said chronometrically operated means being normally ineffective, a cam actuated by operation of said chronometrically operated means, and an arm associated with said cam 60 and movable thereby into close proximity to said evaporator, said arm being adapted, after a predetermined thickness of frost has accumulated on the evaporator, to move in a plane substantially at right angles to the extension of the 65 layer of frost into engagement with the frost to cause said chronometrically operated means to be rendered effective.

13. A refrigerating system including an insulated cabinet having an evaporator located 70

therein, means for automatically controlling said system to cause said evaporator to produce a refrigerating effect, said evaporator having a cooling surface upon which frost accumulates,
5 a device for causing said evaporator to defrost, a chronometrically controlled means for operating said device, said device being normally ineffective for defrosting said evaporator said device including a member actuated at predetermined timed intervals by operation of said

device into close proximity to said cooling surface of said evaporator, and said member being adapted, after a predetermined thickness of frost has accumulated on said cooling surface of said evaporator, to move in a plane substantially at 5 right angles to the extension of the layer of frost into engagement with the frost to cause said defrosting device to be rendered effective.
